UNITED STATES PATENT OFFICE.

JOHN O. NEIKIRK, OF LOMBARD, ILLINOIS.

FIREPLACE.

1,410,341.

Specification of Letters Patent. Patented Mar. 21, 1922.

Application filed January 31, 1921. Serial No. 441,248.

To all whom it may concern:

Be it known that I, JOHN O. NEIKIRK, a citizen of the United States, residing at Lombard, in the county of Du Page and 5 State of Illinois, have invented certain new and useful Improvements in Fireplaces, of which the following is a specification.

This invention relates to fireplaces, and has for its object the production of a fireplace 10 that can be very conveniently and effectively installed and that will present a desirable appearance and at the same time will be very efficient. Other objects of the invention will be apparent from a consideration of the accompanying drawing and the following description thereof.

Fig. 1 of the drawing is a front elevation of a fireplace embodying the features of my invention; Fig. 2 is a side elevation of the 20 same; and Fig. 3 is a vertical central section of the fireplace and chimney along the line 3—3 of Fig. 1.

The central feature of the fireplace comprises an integral casing 5 of cast iron, arranged to enclose the ash pit, the grate, the combustion chamber, and the flue to the chimney, so as to prevent any leakage from these chambers into the walls or into the room, and so as to form a proper support 30 for the mason work and other portions of the walls of the fireplace. It is to be understood, however, that this casing may be built up in any suitable manner, such as by means of plates of metal, cast or rolled, suitably connected together.

The casing 5 comprises a rear wall 6 which extends behind the ash pit 7, the fire-bed chamber 8, and the combustion chamber 9, and supports, at its upper end, a flue 10 through which the burned gases pass from the combustion chamber to the chimney. This flue comprises a horizontal passageway 40 of suitable size positioned near the central upper portion of the casing. The casing also has an upper horizontal plate 11 and a vertical front plate 12, the latter having a wide flange 13 surrounding the opening 14 which allows a suitable draft for the fire and a suitable opening for removing the ashes 50 from the grate.

Any suitable grate may be used in the casing, either for wood or coal; and, as the grate is no part of my invention, it has not been illustrated herein. The floor 15 of the ash pit 55 may be made of any suitable cement or

other material. The front wall 16 in front of the fireplace is supported by the flange 13, and the other walls of the fireplace are built up in any suitable manner, and all of the walls may be of any suitable material. The 60 chimney flue 17 extends downwardly below the flue 10, and any suitable arrangement may be provided for cleaning it out in an ordinary manner. A damper 18 may be inserted in the flue 10 in any suitable manner, 65 with a rod 19 for opening and closing the same.

On the sides of the casing are air spaces 21; in the rear of the casing is an air space 22, and also above the casing is an air space 23, these air spaces being all connected, and throughout these spaces, when the fire is operating, air circulates by entering through 70 grated openings 24 in the lower portion of the sides and passing outwardly through the 75 grated openings 25 in the upper portions of the sides. By these means the air circulating around the casing 5 takes up heat therefrom and is carried into the room and thus prevents waste by conduction outwardly 80 through the walls. This also prevents the casing from becoming overheated, and hence warped or otherwise injured, and reduces the danger of overheating of the walls and thus setting fire to the building. 85

In the rear of the air chamber 22 is placed a vertical sheet 26 which very materially reduces the waste heat. The greater portion of the air in the rear chamber passes upwardly between the sheet 26 and the rear 90 wall of the casing, but a small portion thereof passes between the sheet 26 and the wall 27 of the chimney. Inasmuch as ordinary dry air absorbs but little radiant heat energy it will be seen that the sheet 26 will absorb 95 most of the radiant energy from the wall 6 and will radiate a large portion thereof back to the wall 6, and thus prevent its passing into the wall 27. At the same time the sheet 26 gives two more surfaces of contact for 100 the air and thus materially assists in heating the air. In this manner the air circulation in the rear passageway is materially increased because of the greater amount of heat which the air can absorb in this passageway with reference to the side passageway. 105 As a consequence the air circulates in the rear, although the inlets and outlets for the air are on the sides, and the side air chambers are much larger than the rear chamber. 110

Suitable shutters 28 are placed in the air inlets and outlets, so as to reduce the heating of the room by the fire when desired.

I claim as my invention:

- 5 1. In a fireplace a casing with a rear vertical wall having an opening in the upper portion thereof, and a flange projecting outwardly horizontally a material distance from said wall and surrounding said opening; said casing having a top horizontal wall and a front wall extending downwardly from the front edge of said top wall substantially even with the bottom of said rear wall; said front wall having a large recess 15 in its lower central portion, and a wide horizontal flange extending outwardly from said front wall along the sides and top of said opening.
- 10 2. A fireplace having a casing according to claim 1 and non-conducting walls at the sides and the rear and over said casing, and spaced a material distance therefrom, form-

ing connected air chambers around said casing, said non-conducting walls having air openings therethrough.

25

3. In a fireplace a combustion chamber, a chimney, an elongated horizontal conduit connecting the upper end of said chamber with said chimney, a material distance above the lower end of said chimney, an air chamber surrounding said conduit, and an air inlet and an air outlet connected with said air chamber.

30

4. In a fireplace a combustion chamber, an air chamber partly surrounding said chamber, a plate mounted in said chamber parallel with the wall of said combustion chamber, and spaced away from the walls of both of said chambers, and means for allowing air to pass into and out of said air chamber.

35

40 In testimony whereof, I hereunto set my hand.

JOHN O. NEIKIRK.
